JOSEPH J. KNAPE, OF GRAND RAPIDS, MICHIGAN, ASSIGNOR TO KNAPE & VOGT MANUFACTURING COMPANY, OF GRAND RAPIDS, MICHIGAN, A CORPORATION OF MICHIGAN

ADJUSTABLE SHELF BRACKET

Application filed February 20, 1928. Serial No. 255,721.

This invention relates to adjustable shelf brackets, and it is a primary object and purpose of the invention to provide a simple, economically produced and strong shelf bracket adjustable vertically at intervals, occupying but little space and so constructed that articles of merchandise or the containers thereof may be placed underneath the shelf support practically the full length thereof, there being no space lost because of diagonally positioned members leading from the outer ends of the shelf supports downwardly and inwardly at an angle to the vertical member on which they are attached. The construction for attaining these ends as well as others not at this time specifically stated is fully illustrated in the accompanying drawings, in which,

Fig. 1 is a perspective view showing an embodiment of a shelf support made in accordance with my invention.

Fig. 2 is a vertical section therethrough showing the support as it is being installed or removed from the vertical member.

Fig. 3 is a view similar to Fig. 2, the shelf support being shown in operative position.

Fig. 4 is a perspective view showing the shelf support of my invention.

Fig. 5 is a perspective view showing a different form of the shelf support of my invention.

Like reference characters refer to like parts in the different figures of the drawings.

The vertical member to which the shelf supports are attached is made from sheet metal and includes a central substantially channel like section 1 from which wings 2 extend outwardly in the same vertical plane adapting the same to lie against a vertical wall to which the member may be attached by means of screws. The channel portion of the member has horizontal slots 3 cut therein at vertical spaced intervals.

The shelf support is made from a single piece of metal and includes a horizontal section 4 which at its outer end is bent back upon itself as indicated at 5, continuing as a section 6 which lies substantially parallel to the lower section 4 over which it is located, there being, however, a slight acute angle between the up-

per and under sides of the sections 4 and 6 respectively. The section 6 at its inner free end is divided so as to provide two fingers 7 which pass at opposite sides of the channel portion 1 and an upturned lip 8 adapted to extend through any of the slots 3.

The inner end of the under section 4 is bent downwardly at right angles to make the vertical leg 9 with adjoining portions 10, the leg 9 being offset in a plane in front of the parts 10 so as to lie against the front side of the channel 1 and oppose the front sides of the wings 2, respectively. At its lower end the leg 9 has a lip 11 turned rearwardly at right angles which, at its underside, is formed with a cam surface 12 as fully shown in Figs. 2, 3 and 4.

In applying the shelf support to the vertical member to which it is adjustably attached, the lip 8 is passed through one of the slots 3, as shown in Fig. 2, and the shelf support is then turned in a clockwise direction so as to bring the lip 11 into conjunction with the slot 3 next below the one through which the lip 8 has been passed. The cam under surface 12 of the lip 11 engages against the lower edge of the slot 3 into which it is to be placed and in order to enter the lip it is necessary to apply sufficient force so that the cam underside 12 will ride against and over the under edge of the slot 3 with which it is engaged. By reason of the slightly angular position of the sections 4 and 6 with respect to each other, such sections may be sprung toward each other sufficient distance that the lip 11 may be readily snapped into its slot 3; and the spring stress set up causes the underside 12 of the lip 11 to bear tightly against the lower edge of the slot 3 into which the lip 11 extends, thereby retaining the shelf support securely in place, though such support may be readily removed by application of an upward tilting pressure against the underside of the outer end of the support.

It is evident that the shelf support described occupies a horizontal position and shelves may be carried by resting the same against the upper sides of the section 6. The right angle location of the two parts 4 and 9 with respect to each other makes it possible

to fill the entire space with books, articles of merchandise or the like carried on the shelves. The snap engagement of the shelf supports with the vertical member on which they are mounted insures against accidental displacement of the supports.

In Fig. 5 the shelf support is shown in a somewhat different form. Instead of the leg 9 and adjoining portions 10 being turned 10 downwardly from the under section 5 the leg 9a with adjacent portions 10a are turned upwardly from the inner end of the upper section 6 and the lip 8a is formed at the upper end of the leg 9a. Also the lip 11a is formed 15 at one end of and in the same plane with the section 4 having an undercam surface 12a similar in all respects to the cam surface 12 on the lip 11 previously described.

This shelf support may be applied to the 20 vertical channel member in exactly the same way as the first structure and has all of the advantages thereof and is frictionally held on the vertical support in the same manner.

These devices have proved very practical 25 and satisfactory in service. The invention is defined in the appended claims and is to be considered comprehensive of all forms of structures coming within their scope.

I claim:

30 1. In combination with a vertical sheet metal channel member having wings extending outwardly from the rear edges of the flanges, a shelf supporting member comprising a substantially horizontal section, a second section bent back underneath the first section and slightly spaced therefrom, a third section extending downwardly from the inner end of the second section, said third section having offset portions adapted to oppose the outwardly extending wings of the channel member, a lip extending upwardly from the inner end of the first section and a second lip extending substantially horizontal at right angles to and at the lower end of 40 the third section, substantially as and for the purposes described.

2. A channel member having a shelf supporting member as recited in claim 1 but also characterized by the fact that the aforesaid 50 first mentioned horizontal section has fingers extending from the inner end thereof, said fingers being adapted to contact with the wings on the channel member.

3. In combination with a vertical sheet 55 metal channel member having a plurality of spaced apart slots therein, a shelf supporting member comprising a substantially horizontal section, a second section bent back underneath the first section and slightly spaced 60 therefrom, a third section extending downwardly from the inner end of the second section, said third section having integral portions extending laterally therefrom, said portions being adapted to contact the flanges of 65 the said sheet metal channel for the purpose

described, a lip extending upwardly from the inner end of the first section and a second lip extending substantially horizontal at right angles to and at the lower end of the third section, for the purposes described. 70

In testimony whereof I affix my signature.

JOSEPH J. KNAPE.
